UNITED STATES PATENT OFFICE.

WYNDHAM LIONEL FOLLIOTT FAITHFULL, OF SUSSEX, ENGLAND.

STIRRUP-LEATHER.

1,335,826.

Specification of Letters Patent.

Patented Apr. 6, 1920.

Application filed January 20, 1919. Serial No. 272,178.

To all whom it may concern:

Be it known that I, WYNDHAM LIONEL FOLLIOTT FAITHFULL, a subject of the King of Great Britain, residing at Sussex, England, have invented certain new and useful Improvements in or Relating to Stirrup-Leathers, of which the following is a specification.

This invention relates to the suspension 10 of stirrup irons from a riding saddle.

Under my invention, the stirrup iron is suspended from the saddle by a single strap secured by means of a safety device so made that while holding the strap firmly 15 so long as the stirrup iron is being pressed down, it permits of ready and quick adjustment of the strap when required. The device, should the rider be thrown from his horse, with his foot still engaging the stirrup iron, permits of the strap being entirely 20 released thereby preventing the possibility of the rider being dragged by the horse.

The safety device preferably consists of a member pivotally connected with the 25 saddle, either directly or indirectly, and having a slot therein above which is a bar, or equivalent, preferably parallel to the axes of the hinge pins, or equivalent, on which the plate is pivotally supported, the upper 30 end of the stirrup strap being passed through the slot and partly around the bar, or equivalent, from which the strap extends upward and downward. A downward pressure on the stirrup iron causes the strap to 35 be wedged in and held by the device while an upward pull on the strap relieves the wedging action and leaves the strap free to be easily pulled or adjusted to any position or indeed to be pulled right out of the 40 device in an emergency such as hereinbefore referred to.

The device may be permanently secured to the saddle or it may be removably secured or attached.

45 Rollers or rounded bars may be provided above and below the slot in the plate and the bars above and below the slot may be serrated, if desired, to increase their gripping action.

50 I may provide a bar hinged at its upper end to the saddle and having a bottom and top slot and a central bar behind which the strap is passed; the strap passing in at the bottom slot and out at the top slot. The 55 strap may be suitably marked to indicate

its positions in the holding device for the requirements of different riders.

The turning of the holding member or plate may be limited by a stop or equivalent to insure that the leather strap will be 60 freely adjustable, when required, as the overturning of the strap holding member may take it past the position at which the strap can be pulled through.

In order that the invention may be clearly 65 understood I will now describe the same with reference to the accompanying drawings which show some examples of how the invention may be carried into effect.

Figure 1 shows a saddle with the single 70 stirrup leather and the safety suspending device.

Figs. 2 and 3 are detail front and side elevations of the safety device.

Fig. 4 shows a mode of lacing the single 75 stirrup leather into the safety device.

Fig. 5 shows how the safety device may be modified to suit "Canadian" saddles.

Fig. 6 shows a modified form of the 80 device.

Referring to the drawings:—

The safety device, as shown in Figs. 1 to 85 3, consists of a member *b* pivotally connected to a bracket *b*¹ which is removably carried on the saddle bar *c*. The member *b* has a slot or opening *b*² above which is a bar *b*³ parallel to the axes of the hinge pins *b*⁴ on which the member *b* is pivotally supported. The upper end *a*¹ of the stirrup strap *a*, in the example shown passes through the slot 90 *b*² to the back of the bar *b*³ and then extends upward as shown clearly at Fig. 3. I prefer, in some cases, to use instead of the bracket *b*¹, a simple plate (see Fig. 6) with a slot *b*² and socket parts *e* therein for the 95 hinge pins *b*⁴, of the member *b*, this plate being directly riveted, at *g* to the saddle tree.

The arrangement is such, that a downward pressure on the stirrup iron *d* causes 100 the strap *a* to be wedged between the bar *b*³ and the bracket *b*¹. The strap is therefore held securely in position, so long as the normal position of the rider is maintained, but should the rider be thrown, with his foot 105 still engaging the stirrup iron *d* so that the latter is pulled upward, the member *b* will be turned upward about the hinge pins *b*⁴ and will relieve the wedging action of the bar *b*³ on the strap end *a*¹ with the result 110

that the strap will be left free to easily draw out of the safety device. When the rider is thrown in this way his other foot may be caught in the stirrup on the other side of the saddle which will still be securely held but this is not the real danger as the rider can easily jerk this foot free, but if no means were provided for preventing the other foot and stirrup being caught and pulled over the saddle, the rider would be helplessly hung from the saddle.

Rounded bars are shown both above and below the slot b^2 in the member b .

The strap a may be suitably marked, as shown in Fig. 1, to indicate the positions thereof in the safety device to suit the requirements of different riders.

The turning of the holding member b is, in the example shown, limited by stops b^3 which insure that the member b cannot be overturned and also insure free adjustment of the strap a when required. The overturning of the strap holding member b would take it past the position at which the strap could be pulled through.

At Fig. 4 I have shown how the strap a may be passed over the bar b^3 and its end a^1 brought back behind same and in front of the bar b^6 . The wedging action on the strap is the same as before. The supporting bracket b^1 is modified, having here two loops b^7 engaging the saddle bar c .

Fig. 5 shows a modification of the device adapted for "Canadian" or "Rough Rider's" saddles, the same holding device b being used but in this case the holding member b is pivotally connected with bars d screwed to the saddle.

The advantages of my improved stirrup strap with its safety fastening device are as follows:

There is a saving in leather of at least 50%.

No buckles or tongue holes are required.

The leather straps will wear considerably longer than the old double pattern because straps with buckles first wear out at the tongue holes. The new straps bear the

strain on the whole surface and are in reality stronger.

When the new straps break at the stirrup iron instead of being useless they may be shortened an inch and their use prolonged.

The single straps with their safety devices give perfect security as it is impossible for a rider to be hung up.

The straps are far more easily adjusted when riding and can be lengthened or shortened in a second by the most indifferent horseman, at any pace.

Having only a single width of leather between the knee and saddle greater comfort is obtained.

With the safety device either a new single strap or an old double strap can be used.

Having now fully described my invention what I claim and desire to secure by Letters Patent is:—

1. A safety device for suspending single stirrup straps from riding saddles comprising a stationary member on the saddle, and a buckle member pivotally connected with the stationary member, said buckle member having a cross bar and the stirrup strap being laced through the member behind said bar and adapted to be wedged and held between the same and the stationary member by downward pressure exerted on the strap, substantially as set forth.

2. A safety device for suspending stirrup straps from riding saddle comprising a bracket removably carried on the saddle bar, and a buckle member pivoted to the bracket, said buckle member having a cross bar and the single stirrup strap being laced through the member behind said bar and wedged between the same and the bracket by downward pressure exerted on the strap, substantially as set forth.

In testimony whereof I affix my signature in presence of two witnesses.

WYNDHAM LIONEL FOLLIOTT FAITHFULL.
